SEAM RIPPING DEVICE

Peter A. Schmitt, Modesto, Calif.

Application March 13, 1950, Serial No. 149,307

1. Claim. (Cl. 30—211)

1

This invention is directed to, and it is an object to provide, a novel, manually supported seam ripping device for use by a seamstress, or a housewife during sewing activities.

In altering garments it is necessary that seams be ripped by cutting the stitching, and this is usually a very tedious operation, especially where an open-blade or scissors are used, as great caution must be exercised not to cut the cloth.

The purpose of the present invention is to provide a small, compact, easily manipulated device which may be used, by hand, to cut the stitching along a seam; the device being arranged so that it is impossible to cut or slit the cloth.

A separate object of the invention is to provide a seam ripping device which includes a novel slotted head and a cooperating, movable cutter working within such head; the threads of the stitches of a seam engaging in the slots and being severed by the cutter as the device is manually advanced along the seam.

Another object of the invention is to provide a seam ripping device which is small and light weight.

Still another object of the invention is to provide a seam ripping device which is designed for ease and economy of manufacture.

A further object of the invention is to provide a practical and reliable seam ripping device, and one which will be exceedingly effective for the purpose for which it is designed.

These objects are accomplished by means of such structure and relative arrangement of parts as will fully appear by a perusal of the following specification and claim.

In the drawings:

Fig. 1 is an elevation of the seam ripping device illustrating the manually operated embodiment.

Fig. 2 is a similar view, except that the adjacent side of the thin hollow head is broken away.

Fig. 3 is a transverse sectional elevation of the device shown in Figs. 1 and 2.

Referring now more particularly to the characters of reference on the drawings, as shown in Figs. 1-3, inclusive, the seam ripping device comprises a scissors-like assembly which includes cooperating longitudinal shanks, indicated at 1 and 2, and said shanks are pivoted together, for relative swinging movement, as at 3.

The shank 1 may be termed the fixed shank, while the shank 2 is the movable one thereof.

At the rear ends the shanks 1 and 2 diverge slightly, and are formed with finger loops 4, by

means of which the device is supported and actuated.

At the front end thereof the fixed shank 1 is fitted with a thin hollow head 5, which includes spaced sides 6; such sides being quite close together at the forward part of the head, but having somewhat greater spacing at the rear part of the head.

The forward edge portions of the sides 6 converge and merge at the front edge 7 of the head 5; such convergence assuring that the head may have easy sliding engagement with the pieces of cloth which are secured by the seam or line of stitching to be ripped.

Additionally, the front edge 7 of the head 5 is forwardly arcuate, except at the ends where rounded guide nubs 8 project ahead of the adjacent end of said front edge 7, and form notches 9 with the adjacent ends of the curved edge 7.

The front edge 7 of head 5 is formed with a row of tapering teeth 10 parallel to each other and to the longitudinal axis of the device and leaving thread receiving slots 11 therebetween.

A thin circular cutting disc 12 is journaled in the head 5, as will be hereinafter seen, the disc being of sufficient diameter to lap slots 11; the rounded edge 7 of the head 5 being concentric with the disc. A cutting disc 12 is fixed concentric with a pinion 13 whose hub turns on the spindle-forming portion 14 of a screw 15 mounted in the back side 6 of the head 5. At the end adjacent the pinion 13, the movable shank 2 is formed with a rack 16 which runs in mesh with said pinion, whereby upon repeated opening and closing movement of the finger loops 4 by hand, the pinion 13 and cutter disc 12 are rotated first in one direction and then in the other.

When the device is in use, it is supported from the hand by finger engagement in the loops 4, and then the device is manipulated so that the head 5 advances, between the layers of cloth, lengthwise against the seam or line of stitching 17 to be ripped. Thereafter, with the finger loops 4 being worked relatively in and out, the device is advanced along the seam; the thread comprising the stitching successively entering the slots 11 and being cut by the rotating cutter disc 12. The operation is rapid and effective, and yet there is no opportunity for the cutter disc 12 to cut the cloth adjacent the seam 17.

The guide nubs 8 assure that the device will not run off or away from the seam 17 during the ripping operation. Any mis-alignment of 55 the device will result in the line of stitching

3
catching in a notch 9, and thus not relatively slipping off either end of the head.

The described device provides a handy, practical, and convenient instrument for the rapid and effective ripping of garment forms.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claim.

Having thus described the invention, the following is claimed as new and useful, and upon which Letters Patent are desired:

A seam ripping device comprising a pair of scissors-like shanks pivoted together intermediate their ends, a hollow head projecting forwardly from and secured to the front end of one shank, the other shank movably projecting into the head, said head having thin opposed walls

5 merging toward each other to provide a substantially sharp edge at the outer periphery of the head, there being a row of slots cut through said walls from said outer periphery, and a thin disc cutter mounted within the head for working motion across the row of slots; there being means between the cutter and the other shank to oscillate the cutter upon relative movement of the shanks about the pivot.

PETER A. SCHMITT.
